HENRY W. YOUNGQUIST, OF MANCHESTER, NEW HAMPSHIRE, ASSIGNOR TO
DRAPER CORPORATION, OF HOPEDALE, MASSACHUSETTS, A CORPORATION OF
MAINE.

WARP-TENSION-CONTROLLING MECHANISM FOR LOOMS.

1,391,928.

Specification of Letters Patent. Patented Sept. 27, 1921.

Application filed September 8, 1920. Serial No. 409,000.

To all whom it may concern:

Be it known that I, HENRY W. YOUNGQUIST, a citizen of the United States, and resident of Manchester, county of Hillsborough, State of New Hampshire, have invented an Improvement in Warp-Tension-Controlling Mechanism for Looms, of which the following description, in connection with the accompanying drawing, is a specification, like characters on the drawing representing like parts.

This invention relates to improvements in warp tension controlling mechanism for looms, and the general object of the invention is to provide a mechanism which will let off the warp more uniformly than is accomplished in devices heretofore employed.

In the usual types of let off mechanisms the rotation of the warp beam is controlled by a frictional mechanism or by a pawl and ratchet mechanism which maintains a relatively heavy tension upon the warp at all times and the rotation of the beam is intermittent and more or less jerky.

By the present invention a relatively light tension is normally applied to the warps, preferably through a braking mechanism operating upon the warp beam, and the tension mechanism is locked at a predetermined position of the lay in its beat-up movements, preferably just before the reed engages the fell of the cloth so that the proper tension is maintained upon the warp at the time of the beat-up while the warp is let off smoothly from the warp beam when the locking mechanism is released, thus avoiding the objectionable jerky movement of previous let off mechanisms.

A further object of the invention is to provide a tension let off mechanism which will prevent the breakage of warps when the shuttle becomes misplaced, as by rebounding into the shed during the operation of the loom. In the present invention the tension which is imposed upon the warp may be so light that if a shuttle should rebound into the shed the warp beam would be rotated sufficiently as the shuttle is forced forward by the lay to prevent the breakage of the warp before the tension mechanism is finally locked at the end of the beat-up of the lay.

A further object of the invention is to provide a novel braking mechanism for warp beams of looms which is operable to maintain a predetermined tension upon the warp and at a predetermined position of the lay in its beat-up which will be actuated to lock the warp beam against rotation. 55

A further object of the invention is to provide braking mechanism for the warp beam of the loom of the character described with means for varying the amount of tension normally imposed upon the warps. 60

A further object of the invention is to provide a brake for the warp beam of the loom which can be readily released to enable the warp beam to be removed and replaced without varying the adjustment of the braking mechanism. 65

Further objects and features of the invention will more fully appear from the following description and accompanying drawing and will be pointed out in the annexed claims. 70

A preferred embodiment of the invention is illustrated in the accompanying drawing as applied to the well known Northrop type of loom.

Figure 1 is a transverse sectional view of a sufficient portion of a usual type of loom as is necessary to illustrate the invention embodied therein as applied thereto. 80

Fig. 2 is a rear elevation of a portion of a loom frame showing one end of the warp beam with the braking mechanism embodying my invention applied thereto. 85

Fig. 3 is a detail plan view of the lever mechanism for operating the warp beam brake. 90

Fig. 4 is a detail side elevation of a portion of a preferred form of brake constructed in detachable sections.

Fig. 5 is a plan view of the brake illustrated in Fig. 4 showing a preferred form of interlocking detachable members. 95

The present invention is illustrated herein as applied to a usual type of loom which comprises the usual side frames 1, breast beam 2 and lay 3, which is supported upon swords 4 which are secured to a rock shaft 5 mounted in suitable bearings in the loom sides. The loom sides are also connected by the usual cross girder 6. The loom may 100

and does comprise the other usual mechanisms which, being well known and forming no part of the present invention, need not be illustrated herein.

5 The usual warp beam 7 is mounted upon a shaft 8 which is journaled in suitable open bearings 9 in the loom sides. The warp beam is provided with a brake drum 10 which may be acted upon by any suitable 10 type of braking mechanism which will perform the function of locking the beam against rotation when the lay reaches a predetermined position in its beat-up.

In the preferred construction illustrated 15 the brake comprises sections 11 and 12 preferably made of flexible metal such as steel, which have attached to their ends respectively L-shaped locking members 13 and 14 so constructed that the laterally extending 20 portion 15 of one will engage the laterally extending portion 16 of the other. The co-operating engaging faces of the extensions 15 and 16 are inclined in such a manner as to provide, in effect, hooks which interlock 25 with each other.

A brake shoe 17 which is secured at one end to one of the said sections underlies the brake strap sections 11 and 12 and engages the surface of the drum.

30 When the warp beam is to be removed the tension upon the brake is released as will hereinafter be more fully described, and the interlocking members 13 and 14 disengaged, so that the sections 11 and 12 may be 35 separated and the warp beam lifted from its bearings. Upon the introduction of a new warp beam, the brake sections may be again applied by merely interlocking the detachable members 13 and 14 and the normal tension restored without modifying the 40 adjustment of the tension applying means.

Any suitable means may be provided for actuating the brake band to control the rotation of the warp beam to effect the purpose herein described. In the construction illustrated herein one end of the section 11 of the brake band is rigidly secured to an extension 18 of a bracket 19 which is secured to the loom side. The free end of 45 section 12 of the brake is provided with a clamp 20 which is connected by a hook shaped link 21 to a brake actuating lever which is operated by suitably actuating means and moving in consonance with the 50 movement of the lay and which serves to clamp the brake upon the brake drum with sufficient force to lock the warp beam against rotation when the lay has reached a predetermined position in its beat-up, preferably 55 when the reed is almost in engagement with the fell of the web of the cloth being woven.

The preferred form of brake lever is constructed in two sections which are yieldably connected together in order to prevent the 60 shock of the actuating mechanism from

fracturing the lever. As illustrated, the brake lever comprises a main section 22 having hook shaped end which engages the link 21 and which is pivoted upon a stud 23 projecting from the bracket 19, and a supplemental section 24 which also is pivoted upon the stud 23 and is provided with a downward extension 25 to which the actuating mechanism is connected.

The brake lever sections 22 and 24 desirably are provided with laterally extending bosses 26 and 27 having respectively seats for a heavy spring 28 through which motion is imparted from the supplemental section 24 to the main section 22. This spring is of sufficient strength to transmit the force applied to the supplemental section to the main section to properly actuate the brake, but is adapted to yield enough to prevent breakage caused by any unusual movement of the supplemental section. It also serves as a cushion to reduce the likelihood of crystallization of the parts due to repeated shocks.

Any suitable means may be provided for actuating the supplemental section of the 90 brake lever. As illustrated, the depending end 25 of said supplemental section is connected to one end of link 29, the other end of which is adjustably secured by a set screw 30 in a sleeve 31 which is pivotally connected with the upper end of an arm 32, the lower end of which is pivotally mounted upon a stud 33 upon an arm or extension 34 of the rock shaft 5 which carries the swords which support the lay.

The arm 32 is provided with a lateral extension 35, which lies in the path of one of the swords of the lay so that the latter engages the same during the beat-up movement of the lay, thereby actuating the arm 32, through the link 29, transmitting its movement to the arm 25 of the supplemental section of the brake lever. The movement of the supplemental section in turn actuates the main section 22 of the brake lever and causes the same to apply the brake to the brake drum with sufficient force to lock the warp beam against rotation.

It may be noted that the arm 32 of the rock shaft 5 oscillates with the sword and that the arm 32 is movable relatively to the sword. By reason of this construction, and the adjustable connection between the arm 32 and the link 25 the action of the brake can be so adjusted that the brake will be applied just before the reed engages the fell of the cloth.

Thus a normal, uniform light tension may be maintained upon the warps at all times and the tension mechanism locked after the shuttle has been thrown across the lay and just before the lay beats up the filling.

By thus locking the tension mechanism for the warp threads just before the beat-up takes place, a very light normal tension may

be maintained upon the warp so that if, for any reason the shuttle fails to enter the shuttle box or rebounds therefrom, as sometimes occurs from the breaking of the protector 5 rod and for other reasons, the tension applied to the warp as the reed engages the shuttle will cause the warp beam to rotate sufficiently to prevent breakage of the warp. Furthermore, by thus providing means for 10 releasing the normal light tension on the warp, the warp beam can be readily rotated by the operator when it is necessary to change the warp or to pick out imperfectly woven filling.

15 Any suitable means may be provided for maintaining this light normal tension upon the warp. A convenient means which is illustrated herein, comprises a stop which is in the form of an arm 36 pivotally secured 20 to a bracket 37 upon the cross girder 6, the stop 36 being in a position to engage the depending end 25 of the lever 24 at such a point as to maintain a predetermined tension upon the brake. This stop 36 may be ad- 25 justably held in proper position by any suitable means. As illustrated, the stop 36 is provided with a lateral extension 38 which is engaged by an adjusting screw 39 mounted in a swinging arm or retainer 40, which is 30 pivotally mounted upon a stud 41 projecting from a bracket 42 secured to the cross girder 6, the cross girder 6 being provided with a slot 43 through which the extension 38 projects. A spring 44 surrounding the stem of 35 the screw 39 and abutting at one end upon the retainer 40 and at the other end against the head 45 of the screw serves to prevent the screw from rotation and thereby to hold it in position of adjustment to which it is set 40 by the operator.

The bracket 42 desirably is provided with an offset hook shaped support 46 for the retainer 40 which will hold it normally in operative position but will permit the retainer 45 to be swung out of the path of the extension 38 of the stop 36, thus enabling the pressure which normally is exerted upon the downward extension 25 of the supplemental section of the brake lever, to be removed 50 when it is desirable to rotate the warp beam 3, manually, or to release the brake sufficiently to enable the interlocking sections thereof to be disengaged for the purpose of removing the warp beam.

55 In the operation of the device the parts are assembled as illustrated in Fig. 1, with the adjusting screw 39 so positioned as to cause the stop 36 to impose the desired tension upon the brake through the brake lever. As 60 the lay is oscillated to beat up the filling, the sword upon each forward movement of the lay engages the lug 35 on the arm 32 just before the reed engages the filling which is to be beaten in the fell of the cloth, thereby 65 drawing the link 29 and operating the brake

lever to exert a sufficient tension upon the brake to lock the warp beam against rotation.

When the lay moves rearwardly the locking pressure upon the brake drum is soon 70 released and the arm 25 of the brake lever engaged with the stop 36, thus restoring the normal light tension upon the warp. When it is desired to rotate the warp beam freely or to remove the warp beam, the retainer 40 75 is swung upwardly out of the path of the extension 38 of the stop so that the pressure of the latter against the brake lever is entirely removed, thereby removing all tension of the brake upon the drum and enabling 80 the ends of the section of the brake to be readily detached so that the warp beam can be removed and replaced.

It will be understood that the embodiment of the invention disclosed herein is illustrative and not restrictive, and that various modifications in construction and arrangement of parts may be made within the spirit and scope of the following claims.

Having thus described my invention, what 90 I claim as new and desire to obtain by Letters Patent is:

1. Warp tension controlling mechanism for looms, having a warp beam provided with a friction drum and a brake band anchored at one end engaging said drum, comprising a lever connected to the other end of said brake band, an adjustable stop engaging said lever adapted to maintain a constant normal tension upon said brake band 95 and means operating upon said lever when the lay reaches a predetermined position in its beat-up to cause said brake band to lock the warp beam against rotation.

2. Warp tension controlling mechanism 105 for looms having a warp beam provided with a friction drum comprising a brake band anchored at one end engaging said drum, a brake lever connected to the other end of said brake band, having a main section fulcrumed upon a pivot on the loom side and a supplemental section also fulcrumed upon said pivot, yielding means connecting said lever sections and means operating upon said lever when the lay reaches a predetermined 110 position in its beat-up to cause said brake band to lock the warp beam against rotation.

3. Warp tension controlling mechanism 120 for looms having a warp beam provided with a friction drum comprising a brake band anchored at one end engaging said drum, a brake lever connected to the other end of said brake band, having a main section fulcrumed upon a pivot on the loom side and a supplemental section also fulcrumed upon 125 said pivot, yielding means connecting said lever sections and means operating upon said lever when the lay reaches a predetermined position in its beat-up to cause said brake 130

band to lock the warp beam against rotation, a stop in the path of said lever, adjustable means for positioning said stop capable of being removed from the path of said stop 5 to permit the latter to release said lever.

4. Warp tension controlling mechanism for looms having a warp beam provided with a friction drum comprising a brake band anchored at one end engaging said 10 drum, a brake lever connected to the other end of said brake band, having a main section fulcrumed upon a pivot on the loom side and a supplemental section also fulcrumed upon said pivot, yielding means connecting said lever sections and means operating upon said lever when the lay reaches a predetermined position in its beat-up to cause said brake band to lock the warp beam against rotation, a stop pivotally mounted 15 on the loom frame engaging said lever, a bracket pivotally mounted on the loom frame having an adjusting screw engaging said stop, said bracket being so mounted as to be removable from the path of said stop to enable the stop to be released from engagement 20 with said lever.

5. Warp tension controlling mechanism for looms, having a warp beam provided with a friction drum comprising a brake 30 band anchored at one end engaging said drum, a lever connected to the other end of said brake band, an adjustable stop engaging said lever operating to impose a predetermined tension upon said brake band, and 35 means connected to said lever operable by the movement of the lay, when the lay reaches a predetermined position in its beat-up to cause said brake band to lock the warp beam against rotation.

40 6. Warp tension controlling mechanism for looms, having a warp beam provided with a friction drum comprising a brake band anchored at one end engaging said drum, a lever connected to the other end of said brake band, an adjustable stop engaging said lever operating to impose a predetermined tension upon said brake band, an adjustable link connected to one end of 45 said lever and at its other end to an arm carried by the lay supporting shaft and

means on said arm adapted to be engaged by the sword when the reed of the lay is in close proximity to the fell of the cloth.

7. Warp tension controlling mechanism for looms having a warp beam provided with 55 a friction drum comprising a brake band anchored at one end and engaging said drum, a lever connected to the other end of said brake band, an adjustable stop engaging said lever operating to impose a predetermined tension upon said brake band, a link connected at one end to said lever, an arm pivotally connected to the other end of said link having means adapted to be engaged by the sword upon the beat-up of 60 the lay, said arm being pivotally connected to the rocking shaft upon which the lay is supported, whereby the lower end of said arm is movable with the sword and the arm also movable relatively to the movement of 65 the sword.

8. Warp tension controlling mechanism for looms having a warp beam provided with a friction drum comprising a brake anchored at one end having separable interlocking hooked sections engaging said drum, actuating means connected to the other end of said brake, means for releasing said actuating means to permit detachment of said interlocking sections whereby the warp 75 beam may be readily removed.

9. Warp tension controlling mechanism for looms having a warp beam provided with a friction drum comprising a brake anchored at one end and formed of detachable interlocking sections engaging said drum, a lever connected to the other end of said brake, means for actuating said lever to lock said warp beam against rotation 85 when the lay reaches a predetermined position in its beat-up and adjustable means engaging said lever, for adjusting the normal tension upon said brake, adapted to be released from said engagement to permit detachment of said interlocking sections, 90 whereby the warp beam may be readily removed and replaced.

In testimony whereof, I have signed my name to this specification.

HENRY W. YOUNGQUIST.
